UNITED STATES PATENT OFFICE.

WILLIAM E. JENKINSON, OF FORT WAYNE, INDIANA.

BOOK OF ACCOUNT FOR ELECTRIC LIGHT AND POWER STATIONS.

SPECIFICATION forming part of Letters Patent No. 726,538, dated April 28, 1903.

Application filed June 29, 1901. Serial No. 66,453. (No model.)

To all whom it may concern:

Be it known that I, WILLIAM E. JENKINSON, a citizen of the United States, residing at Fort Wayne, in the county of Allen and State of Indiana, have invented certain new and useful Improvements in Books of Account for Electric Light and Power Stations; and I do declare the following to be a full, clear, and exact description of the invention, such as to will enable others skilled in the art to which it appertains to make and use the same, reference being had to the accompanying drawings, and to the letters of reference marked thereon, which form a part of this specification.

My invention relates to improvements in electric light and power station records; and the object of my improvement is to afford a condensed system of individual accounts so arranged that the several items and amounts of all said accounts may be readily summed in total footings.

I accomplish my object by the set of books consisting of a meter-book, consumer's record, consumer's ledger, and cash-book, ruled and with columns headed, respectively, as illustrated in the accompanying drawings, in which—

Figure 1 is a view showing a page of the meter-book; Fig. 2, a view showing the arrangement of the consumer's record; Fig. 3, a view showing the arrangement of the consumer's ledger, and Fig. 4 is a view showing the arrangement of a page of the cash-book.

The meter-book A is ruled with five vertical columns B upon each page A', ten columns to each folio page. The said columns are headed by spaces C for the entry of the names and addresses of the customers. Beneath the spaces C, in the columns B, are spaces D and lines D', headed with the word

"Annex." Spaces E, beneath spaces D, are respectively headed "Contract No.," and the spaces F are arranged to contain the entries of the numbers of the meters, together with the number of volts and amperes. The spaces G are arranged to contain the entries of the units of measurement, such as watts and ampere-hours, according to the manner in which the particular meter is geared to register, and the entry is made opposite the corresponding word "Watts" or "Amp. Hrs."

by inserting the number of the constant at which the meter is arranged to read. Upon the lower line in the space G is entered the rate of charge per unit of measurement. The amount of the bill is calculated by multiplying the difference of the successive readings by the constant, thus giving the actual consumption of watts, (or ampere-hours, as the case may be,) and the product thereof is multiplied by the rate of charge.

Ranging parallel with the columns B and to the left hand next adjoining thereto is the column H, which contains the heading "Reading for the month of." The lower portions of the columns B and also the column H are ruled laterally with alternate light and heavy lines K and L. In the spaces I, above the said light lines, within the column H, are printed the calendar months, beginning at the bottom of said column and ranging successively upward, and in the spaces J, above the said heavy lines, within the column H, is printed the word "Amount."

Upon the right-hand side of the page A' is arranged an index-tag M, which is marked with a number corresponding with the number of the first of columns B upon the respective folio page, and each succeeding tenth page is provided similarly with a tag M', marked accordingly, preferably in even numbers, as "200," "300," &c. The pages intervening the above-mentioned pages are provided successively upward with tags N, marked with intermediate numbers, as "10," "20," &c. Additional pages, duplicates of the foregoing pages, are arranged in the latter portion of the meter-book A and are provided with tags P, consecutively marked "1," "2," "3," &c. The first of said duplicate pages is also marked with the word "Annex" upon its tag.

The consumer's record A² is arranged with short leaves S and T between each folio page L² M². The page L² has a vertical column B² at the extreme left-hand side for the number of the lines J², which extend laterally across the pages L², S, T, and M² in alinement. Next adjoining the column B² are arranged the vertical columns C², D², and E², headed, respectively, "Contract No.," "Name," and "Kind of service." The columns F², G², H², and I² are arranged in consecutive sets U.

Each of said sets are arranged at their tops for the entry of the months, and the columns F², G², H², and I² are respectively headed "Readings," "K - Watts," "Price," and 5 "Amount" or their abbreviations. Upon the right-hand portion of the page M² is arranged a column N², headed "Memoranda." Each folio page is provided with an index-tag P² and marked with a number according to the 10 contract-numbers entered in the column C² of the respective folio pages. Additional folio pages, duplicates of the foregoing pages, are arranged in the latter portion of the consumer's record A² and are provided, respectively, 15 with tags Q² and R², marked, respectively, "Arc" and "Power." Foot-lines S², T², and U² extend across the bottoms of all said pages and are designated, respectively, by the words "Totals," "Amounts brought 20 forward," and "Amounts carried forward" or suitable abbreviations of the same.

The consumer's ledger A³ is arranged with short leaves S³, T³, U³, V³, and W³ between each folio page L³ M³. The page L³ has a 25 space at the top for the entry of the month and vertical columns arranged and headed successively as follows: C³, "Contract No.;" D³, "Name;" E³, "Unpaid from previous month;" F³, "Arc Amount;" G³, "Incant- 30 descent. Amount;" H³, "Power. Amount;" I³, "Sundry," and K³ "Total." A set of columns N³, headed "Paid," contains the columns O³, P³, Q³, and R³, headed, respectively, "Amount," "Discount," "Rebate," and 35 "When paid." The column X³, headed "Unpaid amount," is arranged at the right-hand side of the latter columns. The page Z³ has a space at the top for the entry of the month and vertical columns the same in number, 40 arrangement, and headings as the foregoing page, with the exceptions of the columns D³ and E³, which are omitted. The page M³ is an exact duplicate of the page Z³, with the 45 addition of the column Y³, headed "Memoranda." The said short pages are provided with index-tags bearing the names of the months successively. Each folio page is provided with an index-tag b and marked with a number according to the contract-numbers 50 entered in the columns C³ of the respective pages. Foot-lines d, e, and f extend across the bottoms of all said pages in alignment and are designated, respectively, by the words "Totals," "Amounts brought forward," and 55 "Amounts carried forward" or suitable abbreviations of the same.

The cash-book h is ruled with the vertical columns j, k, l, and m successively upon the left-hand portion of the page i and headed, 60 respectively, "Month," "Date," "Contract number," and "Name." Upon the right-hand portion are arranged a number of vertical columns in sets n and q, headed, respectively, "Dr." and "Cash cr." In the set n 65 are four columns r, t, u, and w, headed, respectively, "Cash," "Discount," "Rebate," and "Sundry cash," and in the set q are

two columns q' and q", headed, respectively, "Bank" and "Sundry."

In the use of my books, entry is first made 70 in the meter-book A, one of the columns B being allotted to each individual account. The name and address, contract-number, meter-number, unit of measurement, and rate of charge are entered in the respective spaces 75 provided therefor in the columns B. A particular feature of my meter-book is the arrangement for entering the periodical meter-readings successively upward, beginning with the space containing the name of the month 80 when made. The said meter-readings are entered upon the light lines K within the columns B, and the difference is calculated and entered upon the heavy lines L between the successive meter-readings and opposite the 85 word "Amount" printed in the corresponding space J of column H. Should the customer have additional meters, it is noted in the space D, and an additional account is 90 opened in a like column in the portion of the meter-book marked "Annex." The difference of the meter-readings, as entered upon the lines L of the meter-book, are posted into the consumer's record A² in the column F² upon the horizontal lines J², opposite the names of 95 the corresponding accounts which are entered in the column D², and the kind of service for which the entry was made is noted in the column E². In the columns G², H², and I² are entered the computed amounts of 100 current consumed, rate of charge, and amount charged, respectively. In each of the succeeding sets of columns U are entered the data and computations for the months following, which sets of columns are distinguished 105 from one another by entering at the top of each set the name of the corresponding month. Upon the lines S², T², and U² are entered, respectively, the sums of the entries in the corresponding columns, the amounts brought 110 forward from the preceding page, and the sums of the amounts in the two former lines.

In the cash-book h are entered in the general-debit set of columns n the amounts paid, the discount, and the rebate, respectively, in 115 the columns headed accordingly. Such payments as are received for unclassified charges are entered in the sundry-cash column w and is handled separately as such.

The computed amounts charged in the consumer's record A² are posted into the consumer's ledger A³ upon the horizontal lines J³, opposite the names of the corresponding accounts which are entered in column D³ and in one of the vertical columns F³, G³, or H³, 125 according to the class of service for which such charges were made.

The amounts unpaid remaining to the debit of the respective accounts are entered in the column E³, and the sums of the foregoing entries are entered in the column K³. From the cash-book h are posted in the columns O³, P³, Q³, and R³, respectively, the amounts paid, amounts of discount, rebates, and dates

of payment, and in the column X³ are entered the computed amounts remaining to the debit of the respective accounts. Upon the lines d, e, and f are entered, respectively, the sums 5 of the entries in the corresponding columns, the amounts brought forward from the preceding page, and the sums of the amounts in the two former lines. By the use of my set of books the complex and laborious art of 10 accounting of this particular class is materially simplified and has further advantage of showing at any stage the totals of all amounts entered.

Having described my invention, what I 15 claim as new, and desire to secure by Letters Patent, is—

In electric light and power station records, a set of books consisting of a meter-book having vertical columns for individual accounts 20 arranged with top spaces for the entry of the name and address of the customer, the reference-space marked "Annex," spaces for the entry of the contract and meter numbers, unit of measurement, and the rate of charge, 25 a series of alternate light and heavy lines ranging horizontally through said columns beneath said spaces, and a vertical column at the side of the former columns, containing the names of the months in the spaces between 30 said heavy lines, beginning at the bottom and ranging successively upward; a consumer's record having vertical columns headed respectively "Contract number," "Name," and "Kind of service," and successive sets of 35 columns U arranged to contain the month at

the top, and subdivided into columns headed respectively "Meter-readings," "K-Watts," "Price" and "Amount," and horizontal lines at the bottoms of said columns to contain respectively the sums of the amounts entered in said columns, the amounts brought forward, and the respective sums of the two foregoing amounts; a cash-book having vertical columns to contain respectively the headings "Month," "Date," "Contract number," 40 and "Name," and a set of columns n headed "Dr." and subdivided into columns headed respectively "Cash," "Discount," "Rebate," and "Sundry cash," and a consumers' ledger having vertical columns headed respectively 45 "Contract number," "Name," "Unpaid amount," "Arc amount," "Incandescent amount," "Power amount," "Sundry" and "Total," a set of columns N³ headed "Paid" and subdivided into columns headed respectively 50 "Amount," "Discount," "Rebate," and "When paid," another column headed "Unpaid amount," and horizontal lines at the bottoms of said columns to contain respectively, the sums of the amounts entered 55 in said columns, the amounts brought forward, and the respective sums of the two foregoing amounts.

In testimony whereof I affix my signature in presence of two witnesses.

WILLIAM E. JENKINSON.
